ATTORNEYS.

UNITED STATES PATENT OFFICE.

SAMUEL B. GIRDLER, OF MONTCLAIR, NEW JERSEY.

RECEPTACLE.

Application filed January 27, 1925. Serial No. 5,009.

This invention relates, generally, to improvements in receptacles; and, the present invention has reference, more particularly, to a novel and simple, as well as an ornamental construction of receptacle, which is adapted for use as a safety device, into which may be deposited blades of the safety razor type, after such blades have become useless.

The present invention has for its principal object to provide a novel, simple and neat device, which may be used in the dressing room, for the reception of used and discarded safety-razor blades, the device comprising a main ornamental casing or shell to be used as a permanent fixture in the dressing room, and a blade-receiving receptacle, nested and removably disposed within said casing or shell, into which the discarded razor-blades are deposited and collected, the filled blade-receiving receptacle being removed from the casing or shell for final disposal of the said receptacle and the blades contained therein.

Other objects of the present invention not at this time more particularly enumerated will be clearly understood from the following detailed description of the present invention.

With the various objects of the present invention in view, the said invention consists, primarily, in the novel receptacle for the collection of discarded safety-razor blades hereinafter set forth; and, the said invention consists, furthermore, in the novel arrangements and combinations of the various devices and parts, as well as in the details of the construction of the said parts, all of which will be more fully described in the following specification, and then finally embodied in the clauses of the claims which are appended to and which form an essential part of the said specification.

The invention is clearly illustrated in the accompanying drawings, in which:

Figure 1 is a side elevation of a receptacle showing one embodiment of the principles of the present invention, illustrating in connection therewith, means for the attachment of the device to the wall of the dressing room, or the like; and Figure 2 is a front face view of the said device.

Figure 3 is a transverse vertical sectional representation of the receptacle; Figure 4 is a top view of the same; and Figure 5 is

a horizontal sectional representation of the receptacle.

Figure 6 is a side elevation of the receptacle, showing in connection therewith certain attachments, as a shelf and a razor-holding rack; Figure 7 is a front elevation of the device; and Figure 8 is a top or plan view of the same.

Figure 9 is a side elevation of still another modified form of receptacle embodying the principles of the present invention.

Similar characters of reference are employed in all of the said above described views, to indicate corresponding parts.

Referring now to the said drawings, the reference-character 1 indicates the complete receptacle, the same comprising a main outer shell or casing 2, usually of metal, although it may be made of any other suitable material, in which is removably disposed an inner receptacle 3, made of an inferior material, such as card-board or the like. In the accompanying drawings, the receptacles 2 and 3 are shown in the shape of cylinders, but it will be evident that they may be of any other suitable shape.

As shown, the said main shell or casing is closed at one end by a member 4, so as to form a bottom, said member being suitably secured in a fixed position to said shell or casing. The said member or bottom 4 is also formed with a suitably shaped finger-receiving opening 5, and with a suitable arrangement of upwardly projecting pins or studs 6. The upper open end-portion of the said main shell or casing 2 is provided with a removable cover 7, formed with an annular flange 8 adapted to be fitted in said open end-portion of the said shell or casing, and provided with a laterally extending pin or stud 9, or similar means, adapted to enter a slot 10 with which the said shell or casing 2 is provided, for holding said cover in a predetermined position for the purposes to be presently more fully set forth. The said cover 7 is also formed with an elongated opening or slot 11 and with a suitably constructed lifting means 12, in the form of a handle, or the like.

At its rear portion, the said main shell or casing 2 is provided with rearwardly extending portions, as 13, bent laterally in opposite directions, as at 14, said portions 14 being provided with grasping members 15. A suitably formed fastening plate 16, or the

like, is held between the said grasping members 15, said plate being secured by means of screws 17, or other suitable fastening means, to the woodwork of the wall of the dressing room, or the like.

5 If desired, at the lower end-portion of the said plate 16, there may be an arrangement of a suitably formed bracket 18, provided with a shelf 19, which may be suitably 10 forked, as at 20, for suspension therefrom of a safety-razor.

If desired, in some cases, there may also be attached to the upper end-portion of the fastening plate 16, a suitably shaped shelf 15 or tray, as 21, for storing therein unused razor-blades, soap, or the like.

The previously mentioned inner receptacle is closed at its ends by members 22 and 23. The lower member 22 is provided with perforations or holes 24 corresponding to the location of and for the reception of the previously mentioned pins or studs 6 of the outer casing bottom 4, and the upper member 23 is formed with a laterally extending and elongated receiving slot or opening 25 corresponding to the location of the slot or opening 11 with which the cover 7 of the main shell or casing 2 is provided. The pins or studs 6, when engaged with the perforations 24, hold the inner receptacle in predetermined position so that the slot 25 thereof is properly aligned with the slot 11 in the outer casing cover 7.

In lieu of providing the receptacle 1 with 35 the means of attachment shown in the hereinabove described Figures 1 to 8 inclusive, the main shell or casing 1 may be provided with flanged members 26, as indicated in figure 9 of the drawings, which are suitably perforated for the reception of the fastening screws 27, for attachment of the device to the wall, or the like.

Of course, I am aware, that various other changes may be made in the general arrangements and combinations of the various devices and parts, as well as in the details of the construction of the said parts, without departing from the scope of the present invention as set forth in the foregoing description. Hence, I do not limit my present invention to the exact arrangements and combinations of the various devices and parts, as described in the said specification, nor do I confine myself to the exact details of the construction of the said parts, as illustrated in the accompanying drawings. From the foregoing description, it will be seen, that I have devised a simple and ornamental device, which is most useful for the collection of discarded safety-razor blades, which are inserted in the slot or opening 11 of the main shell or casing, and then permitted to drop through said slot or opening 11, into and through the slot or opening 25 of the inner receptacle 3, so as to be collected within said

inner receptacle. When the said inner receptacle has been filled with the discarded blades, by removing the cover 7 from the main or outer receptacle, said inner receptacle may be readily withdrawn for final 70 disposal of said inner receptacle and the used razor-blades contained therein. The discarded receptacle is thereon replaced by another, the replacing receptacle being properly engaged upon the pins or studs 6, so that 75 it assumes a fixed position against rotation within the main or outer receptacle. The cover 7 is then replaced in predetermined position upon said outer receptacle, so as to bring the slots 11 and 25 into alinement, 80 whereby the device is ready to receive another supply of used and discarded razor-blades, as will be evident.

I claim:—

1. A used safety razor blade receiver comprising a permanent outer casing having a slotted cover, an inner removable and discardable receptacle of inferior material having closed ends, the upper end of said inner receptacle having a slot for alignment 85 with the slotted cover of said outer casing, and means to prevent accidental displacement of said inner receptacle from operative assembled relation to said outer casing.

2. A razor blade receiver comprising a 95 holder, studs in the bottom of the holder and a receptacle with recesses to receive the studs to prevent rotation of the receptacle, the holder and the receptacle each having a slot which slots are aligned when the receptacle is in position within the holder.

3. A receptacle of the character specified comprising a main outer receptacle and a second receptacle therein, said receptacles being both provided with alined receiving openings, for insertion of an article through the opening of the outer receptacle into said inner receptacle, said outer receptacle being provided upon its base with positioning studs, and the inner receptacle being formed 110 in its base with perforations for reception of said studs.

4. A receptacle of the character specified comprising a main outer receptacle consisting of a shell provided at one end with a 115 base, said base being formed with a finger-receiving opening, a cover upon the other end of said shell, said cover being provided with a receiving opening, means co-operating with said shell and cover for positioning the latter upon said shell, and a second receptacle within said main receptacle, said second receptacle comprising a closed base and a closed top, said top being provided with a receiving opening in alinement 125 with the receiving opening in the cover of said outer receptacle, for insertion of an article through the opening of said cover into said inner receptacle.

5. A receptacle of the character specified 130

- comprising a main outer receptacle consisting of a shell provided at one end with a base, said base being formed with a finger-receiving opening, a cover upon the other 55
 6 end of said shell, said cover being provided with a receiving opening, means co-operating with said shell and cover for positioning the latter upon said shell, and a second receptacle within said main receptacle, said 60
 10 second receptacle comprising a closed base and a closed top, said top being provided with a receiving opening in alinement with the receiving opening in the cover of said outer receptacle, for insertion of an article 65
 15 through the opening of said cover into said inner receptacle, combined with means co-operating with said receptacles for maintaining the alined relation of said openings. 70
6. A receptacle of the character specified 75
 20 comprising a main outer receptacle consisting of a shell provided at one end with a base, said base being formed with a finger-receiving opening, a cover upon the other end of said shell, said cover being provided with a receiving opening, means co-operating with said shell and cover for positioning the latter upon said shell, and a second receptacle within said main receptacle, said second receptacle comprising a closed base and a closed top, said 80
 25 top being provided with a receiving opening in alinement with the receiving opening in the cover of the outer receptacle, for insertion of an article through the opening of said cover into said inner receptacle, combined with means co-operating with said receptacles for positioning the inner receptacle within the outer receptacle. 85
8. A receptacle of the character specified 90
 30 comprising a main outer receptacle consisting of a shell provided at one end with a base, said base being formed with a finger-receiving opening, a cover removably disposed upon the other end of said shell, said shell being provided with a stud-receiving slot, a stud extending from said cover into said slot for positioning said cover, said cover being further provided with a receiving opening, and a second receptacle within said main receptacle, said second receptacle comprising a closed base and a closed top, said 95
 35 top being provided with a receiving opening in alinement with the receiving opening in the cover of the outer receptacle, for insertion of an article through the opening of said cover into said inner receptacle, combined with means co-operating with said receptacles for positioning the inner receptacle within the outer receptacle. 100
9. A receptacle of the character specified 100
 40 comprising a main outer receptacle consisting of a shell provided at one end with a base, said base being formed with a finger-receiving opening, a cover removably disposed upon the other end of said shell, said shell being provided with a stud-receiving slot, a stud extending from said cover into said slot for positioning said cover, said cover being further provided with a receiving opening, and a second receptacle within said main receptacle, said second receptacle comprising a closed base and a closed top, said top being provided with a receiving opening in alinement with the receiving opening in the cover of the outer receptacle, for insertion of an article through the opening of said cover into said inner receptacle, said outer receptacle being provided upon its base with positioning studs, and the inner receptacle being formed in its base with perforations for reception of said studs.
- In testimony that I claim the invention set forth above I have hereunto set my hand this 23rd day of January, 1925.
- SAMUEL B. GIRDLER.
